(57) **CLAIM**

The ornamental design for an incense burner, as shown and described.

DESCRIPTION

FIG. 1 is a front, right and top perspective view of an incense burner, showing my new design;

FIG. 2 is a rear, left and bottom perspective view thereof; FIG. 3 is a perspective view of the incense burner in a detached state;

FIG. 4 is a front view thereof;

FIG. 5 is a rear view thereof;

FIG. 6 is a right side view thereof;

FIG. 7 is a left side view thereof;

FIG. 8 is a top plan view thereof;

FIG. 9 is a bottom plan view thereof;

FIG. 10 is an enlarged view of portion of FIG. 1 thereof;

FIG. 11 is an enlarged view of portion of FIG. 2 thereof; and,

FIG. 12 is an enlarged view of portion of FIG. 2 thereof.

The dash-dash broken lines shown in the drawings illustrate portions of the incense burner that form no part of the claimed design. The dot dash broken lines depict the boundaries of the enlargements that form no part of the claimed design.
